UNITED STATES PATENT OFFICE.

OTTO ROTHSCHILD, OF CHARLOTTENBURG, GERMANY.

PROCESS OF MAKING SOUND-DAMPING INTERMEDIATE LAYERS.

1,094,477.

Specification of Letters Patent. Patented Apr. 28, 1914.

Application filed August 15, 1912. Serial No. 715,203.

To all whom it may concern:

Be it known that I, OTTO ROTHSCHILD, a subject of the King of Prussia, residing at Charlottenburg, in the Kingdom of Prussia, German Empire, have invented certain new and useful Improvements in Processes of Making Sound-Damping Intermediate Layers; and I do hereby declare the following to be a full, clear, and exact description of the invention, such as will enable others skilled in the art to which it appertains to make and use the same.

The subject-matter of my invention is an improved process of making sound-damping intermediate layers.

Intermediate layers composed of pieces of natural cork mounted in an iron frame are well known. They have, however, the disadvantage that in hot work-shops the moisture contained in the cork gradually evaporates, causing the cork to shrink so greatly that it is no longer held by the iron frame surrounding it. It has heretofore been endeavored to obviate this defect by impregnating the cork with tar-oil. The elastic properties of the cork are, however, thereby impaired.

In the drawing the figure is a perspective view of the frame holding the cork in place.

According to my invention, I obviate the

defect by heating the cork so highly, before it is placed into the iron frame, that all moisture is expelled from the cork. When the volume of the cork *a* is a minimum it is pressed into an iron frame *b*, then placed in moist chambers, in order that it can absorb moisture, and is then covered by a protective coating of asphalt. If any moisture now escapes through the coating, the volume of the cork can at least be equivalent to that obtaining when no moisture was contained in the same, and will not fall out of the frame because it was pressed into the same when it had this volume.

I claim:

A process of making sound-damping means comprising an iron frame surrounding cork, which consists in heating natural cork and thereby expelling substantially all the moisture therefrom, and diminishing the volume of the same, in thereupon pressing the cork into the iron frame, and in subsequently coating the cork with asphalt.

In testimony whereof I affix my signature in presence of two witnesses:

OTTO ROTHSCHILD.
